UNITED STATES PATENT OFFICE.

PHILIP DE LEMME, OF NEW YORK, N. Y.

DESIGN FOR A TOY DOG.

Application filed January 31, 1927. Serial No 20,567. Term of patent 3½ years.

To all whom it may concern:

Be it known that I, PHILIP DE LEMME, a citizen of the United States, and a resident of New York city, New York, have invented a new, original, and ornamental Design for a Toy Dog, of which the following is a specification, reference being had to the accompanying drawing, forming a part shown. thereof.

In the drawings; Fig. 1 is a view in side elevation of a toy constituting an embodiment of my new design and; Fig. 2 is a plan view looking down upon the showing of Fig. 1.

I claim:

The ornamental design for a toy dog as

PHILIP DE LEMME.
